UNITED STATES PATENT OFFICE

ROSS J. ELLSWORTH, OF WOODSTOCK, ILLINOIS, ASSIGNOR TO HOLMES DISAPPEARING BED COMPANY, OF WOODSTOCK, ILLINOIS, A CORPORATION OF ILLINOIS

BED END

Original application filed April 28, 1927, Serial No. 187,391. Divided and this application filed May 1, 1930. Serial No. 448,827.

This invention relates to disappearing or concealed beds of the type generally designated as recess beds, wherein the bed, when folded or elevated, is positioned in a wall recess or closet and when lowered or unfolded is located for use in the body of a room, and is a division of Application, Serial No. 187,391, filed April 28, 1927.

10 The bed, embodying the principles of this invention, has for its object the utilization of a limited or confined space, whereby a bed when collapsed or elevated into a compact assembly may be completely enclosed therein, and yet afford sufficient room to permit full, 15 free and unrestricted operation thereof.

Furthermore, the construction of the present bed involves a sectional bed end, which is adapted to operate from the movement of the bed frame and thereby regulate the relative positions of the sections thereof in order to reduce the radius of the circle defining the path of movement of the bed end when the bed is being manipulated.

With the above and other objects in view, 25 as will be apparent, this invention consists in the construction, combination and arrangement of parts, all as hereinafter more fully claimed, described and illustrated in the accompanying drawings, wherein

30 Fig. 1 is a vertical side elevation of the present bed illustrating the bed frame lowered and extended in full lines, and elevated or collapsed in dotted lines, and the positions assumed by the several elements when the bed frame occupies these positions;

Fig. 2 is a vertical section taken along line 2-2 of Fig. 1;

40 Fig. 3 is a horizontal sectional view taken along line 3-3 of Fig. 1 through the recess or closet to illustrate a portion of the structure; and

45 Fig. 4 is an enlarged perspective view illustrating in detail the hinged connection between the sections of the bed end.

50 Heretofore recess beds, wherein the lowering of the bed frame causes the end thereof in the recess or closet to swing from the vertical to the horizontal, and the raising of the frame reverses the movement of the bed frame, having required a relatively deep clos-

et or recess to accommodate the movement or swing of the frame and such bed end as may be secured thereto. The present invention contemplates a construction whereby a bed end is secured to the bed frame in such manner that it may be collapsed or folded when the bed frame is elevated, and the collapsing or folding thereof may be controlled from the movement of the frame. Thus, a full size bed end may be used and attached to the inner end of the bed frame and at the same time the depth of the closet or recess may be materially reduced.

Reference being had to the drawings, 10 designates a recess or closet opening into a room by means of a wall opening 11 adapted to be closed by the doors 12.

In carrying out the present invention a pair of tracks 13 are fixed to the floor of the recess or closet 10 and extend from the rear wall thereof to the approximate plane of the outer surface of the front or room wall containing the wall opening 11. These tracks are of angle iron and have the upright webs 14 thereof facing one another as the horizontal webs 13 lie on the floor in spaced horizontal positions. The horizontal web 13 of each track is provided with a flange 15 along the edge thereof opposed to the web 14 which, at a point removed from the track 13, is bent inwardly toward the upright web 14 where it rests parallel to and spaced from the track 13 to form a keeper 16. The inner edge of the keeper 16 is spaced horizontally from the upright web 14 of the track 13 to permit the reciprocation of the bed carriage between it and said upright web 14 as will be hereinafter more fully described.

Cooperating with each track 13 is a horizontal angle bar 17, one arm of which rests 90 parallel to and operates flush against the upright web 14 of the track 13 while the other horizontal arm thereof rests parallel to and upon the track 13 beneath the keeper 16. At its forward end the angle bar 17 has a right-angular vertical extension 18. It will be observed from Fig. 1 that the keeper 16 does not extend throughout the entire length of the track 13 but on the contrary is coextensive with the inner or rear portion 100

only of the track 13 so that the cooperating angle bar 17 may reciprocate on the track 13 with its horizontal arm or web between the track 13 and the keeper 16 and its vertical arm or web operating between the edge of the keeper 16 and the vertical web 14 of the track 13.

To facilitate the movement or reciprocation of the angle bars 17 and their vertical extensions 18 with reference to the tracks 13, each extension 18 has a bracket 19 adjoining the front face thereof, which carries a roller 20 bearing upon the upper surface of the cooperating track 13 in advance of the angle bar 17 and its extension 18.

Thus it is apparent that each angle bar 17 is free to move inwardly on its cooperating track 13 until its vertical extension 18 contacts with the forward end of the keeper 16.

This movement of the angle bar 17 is assisted by the retractile coil spring 21 interposed between the vertical extension 18 of the bar 17 and the upwardly curved arm 22 formed from the rear end of the keeper 16.

These angle irons 17, together with their vertical extensions 18, are combined to constitute a movable carriage for the bed, and to that end the vertical extensions are connected by the horizontal angle bar 23 which is riveted or otherwise secured at its ends to the front faces of said vertical extensions 18. This bar 23 is so positioned that one of its arms or webs extends horizontally in advance of the vertical extensions 18 (as shown in Fig. 1) and thereby creates a support to the under side of which are attached the brackets 19 for the rollers 20. Thus the rollers 20 are positioned in advance of the carriage and below the horizontal bar 23 to operate on the tracks 13.

A bed frame 24 is pivoted, as at 25, to the vertical extensions 18 of the carriage adjoining their upper ends. The pivot 25 of the bed frame 24 is somewhat removed from the end of said bed frame, whereby a portion of the frame projects beyond the extensions 18 toward the recess 10 when the bed frame is in its horizontal position. This projecting end of the bed frame 24 has an L-bracket 26 rigidly secured to each side rail thereof. By so fixing the brackets 26, one arm of each bracket projects at right angles to the bed frame 24 below the plane of the frame when in its horizontal position.

For the purpose of causing the movement of the carriage relative to the tracks 13, the free ends of the right angularly projecting arms of the brackets 26 are pivotally connected to the ends of the links 27. The rear ends of the links 27 are pivoted to the studs 28 formed from or rigidly connected to the rear ends of the vertical arms or webs 14 of the tracks 13. If desired, these links 27 may be pivoted directly to the rear end of the vertical arms or webs 14 of the tracks 13 in

such manner that the pivots will in no way interfere with the movement of the horizontal angle bars 17 forming a part of the carriage.

When the bed frame 24 occupies a vertical position with its side rails adjoining and approximately parallel to the vertical extensions 18 of a carriage, the links 27 occupy substantially horizontal positions parallel to and adjoining the right-angularly projecting arms of the brackets 26 carried by the bed frame. As the bed frame 24 is lowered, the studs 28 of the links 27 being fixed cause the links to exert a pushing force upon the bed frame 24 and through it to the vertical extensions 18 of the carriage. This pushing force causes the carriage to move outwardly from the recess or closet.

Upon the elevation of the bed, i. e. upon its movement from a horizontal to a vertical position, the links 27 exert a pulling force upon the bed frame 24 and through it upon vertical extension 18 of the carriage. This pulling force by the links automatically causes the carriage to move into the recess or closet 10 so that when the bed has reached a vertical position, all of the elements of the installation are contained entirely within the said recess or closet. It will be observed that this movement of the carriage into and out of the recess or cabinet 10 is automatically and entirely controlled from the movement of the bed with respect to the carriage.

In order to economize the space required for the depth of the recess or cabinet 10, the end of the bed carried by the inwardly projecting end of the bed frame 24 and usually the head end, is made in two sections. The lower section 29 of the head end is pivoted to the inner end of the bed frame 24 and its pivots are therefore spaced from the angles of the brackets 26. This positioning of the pivots of the lower section 29 permits the links 27 to rest flush against and parallel to the right angularly projecting arms of the brackets 26 when the bed is elevated and positioned within the recess or closet 10. The upper section 30 of the head end is pivoted to the lower section 29 by any suitable pivot construction. An example of such a pivot or hinge construction is a strap 30^a, pivoted at one end as at 30^b to the interior of the lower end section 29 and at its opposite end, as at 30^c to the exterior of the upper end section 30. A link 31 is interposed between the lower end of each side of the upper section 30 and the upper extremity of the adjoining vertical extension 18 of the carriage. A similar link 32 is interposed between each side of the upper end of the lower section 29 and the cooperating vertical extension 18 of the carriage at a point above the bed frame 24. The connections between these links 31 and 32 and their respective sections 30 and 29 of the head end and the vertical extensions 18 of the carriage are pivotal and in the cases of the end sections

120
125
130

29 and 30 constitute the respective pivots 30^b and 30^c by which the straps 30^a are also pivoted to the end sections.

When the bed is in its horizontal position 5 as illustrated in Fig. 1 the sections 29 and 30 occupy the same vertical plane, one above the other, and together constitute the end of the bed. As the bed frame 24 is swung about its pivot 25 the portion thereof projecting rear- 10 wardly beyond the vertical extensions 18 of the carriage swings downwardly. This downward movement of the inner end of the bed frame causes the links 31 and 32 to also swing downwardly about the pivotal connec- 15 tions thereof to the extensions 18.

The joint between the sections 29 and 30 of the head end is broken as a consequence, whereby the upper section 30 occupies a substantially vertical position irrespective of the 20 position of the bed frame and at the completion of the upward movement of the bed frame, rests substantially parallel thereto. On the other hand the lower section 29 of the 25 head end assumes a position which may be said to be generally horizontal at the end of the upward movement of the bed frame 24 and occupies a position at somewhat of an angle to the upper section 30. Insofar as the movement of the bed frame 24 about its pivot 25 is concerned the vertical extensions 18 constitute fixed pivots for both the bed frame 24 and the links 31 and 32. The opposite ends 30 of the links 31 and 32 being respectively pivoted to the sections 30 and 29 of the bed 35 frame have movable pivots. In this manner the swing of the pivots resulting from the movement of the bed frame 24 about its pivots 25 causes the sections of the head end to assume the positions heretofore described when 40 the bed is elevated and contained within the recess or closet 10.

Reversely, when the bed is lowered from its vertical position within the recess or 45 closet 10 to assume a horizontal position in the room, the movement of the bed relative to the extensions 18 of the carriage causes the links 31 and 32 to swing about their fixed 50 pivots to gradually elevate the sections 30 and 29 until they occupy the same vertical plane and constitute a head of the bed.

By reference to Fig. 1 of the drawings, it is manifest that when the bed frame carries the usual springs and mattress, these elements will be positioned between the upper 55 section 30 of the head end and the bed frame 24 and that the upper section 30 will rest parallel and close to the mattress carried by the bed frame 24. A consideration of Fig. 1 of the drawings will also demonstrate that 60 the bed when elevated or contained within the closet or recess 10, requires a space not greatly exceeding the combined thickness of the head end, mattress, springs and the bed frame 24. The movement of the head end of 65 the bed within the closet or recess 10 is con-

fined within these limits. That is to say, upon the lowering of the bed frame 24 to assume a horizontal position, the upper section 30 moves upwardly and outwardly in substantially a vertical position while the lower section 29 moves upwardly and outwardly and at the same time gradually assumes a vertical position at right angles to the bed frame 24 and in the same vertical plane as the upper section 30.

The lower section 29 carries the bars 33 which when the bed is elevated acts as a support for the elements carried by the bed frame 24 such as the springs and mattress particularly the latter.

To assist in elevating the bed, the angle bar 34, interposed between the side rails of the frame 24 to the rear of the pivots 25 between it and the vertical extensions 18 of the carriage, acts as an anchor for the upper ends 80 of the counterbalance coil springs 35. The lower ends of these springs 35 are anchored to the vertical web of the horizontal angle bar 23 connecting the vertical extensions 18 to form the carriage.

From the foregoing it is apparent that the bed may be collapsed and folded into a closet of extremely shallow depth as compared to the recesses or closets required for the prior beds and in addition thereto may be automatically moved from the closet for occupancy and use.

What is claimed is:

1. The combination with a support, of a bed frame pivoted thereto, a sectional bed end cooperating with the frame, connections between the sections of said end whereby they may move relatively and a connection between each section of the bed end and said support whereby the movement of the frame causes a relative movement of the said sections.

2. The combination with a support, of a bed frame pivoted thereto, a bed end section pivoted to said frame, a second bed end section hinged thereto, and independent connections between the support and each of said end sections for the movement thereof upon the movement of the frame.

3. The combination with a support, of a bed frame pivoted thereto, an end section hinged to the end of the frame, a second end section hinged to the first, and connections between the sections and the support whereby the sections move relatively to each other and to the frame upon the movement of the latter relatively to the support.

4. The combination with a support, of a bed frame pivoted thereto, an end section hinged to said frame, a second end section hinged to the first, a link connecting the first section to the support and a second link connecting the second section to the support.

5. The combination with a support, of a bed frame so pivoted thereon that a portion

of the support extends beyond its pivot, a sectional bed end pivoted to said frame, the sections thereof being pivoted one to the other and a link connecting each section of the bed end to the extending portion of the support.

6. The combination with a support, of a bed frame mounted for movement relative thereto, an end section carried by said bed frame made up of a plurality of sections, one pivoted to the other and to the bed frame, and connections between each section of the bed end and said support.

7. In a bed the combination with a support, of a bed frame pivoted thereto to rest either horizontally or vertically, a bed end movably carried by said frame and comprising a plurality of connected, relatively movable sections, and means connecting the sections individually to the support whereby the end sections assume coplanar positions at substantial right angles to the frame when located horizontally and when the frame moves to a vertical position one of the end sections occupies a position at an acute angle to the frame and the remaining section rests parallel to the frame.

8. In a bed the combination with a support, of a bed frame pivoted thereto to rest either horizontally or vertically, a bed end movably carried by said frame and comprising a plurality of connected, relatively movable sections and means comprising links connecting the individual sections to the support whereby the movement of the frame from vertical to horizontal positions causes the end sections to assume coplanar positions at substantial right angles to the frame and the movement of the frame from horizontal to vertical positions causes the end sections to assume positions parallel and at acute angles to the frame.

9. In a bed the combination with a support, of a bed frame pivoted thereto to rest either horizontally or vertically, a bed end movably carried by said frame and comprising a plurality of connected, relatively movable sections and means operating between the several end sections and the support whereby the movement of the frame relatively causes the end sections to collapse as the frame assumes a vertical position and to become coplanar and at right angles to the frame as the latter assumes a horizontal position.

ROSS J. ELLSWORTH.
